STATIONERY FORM AND ENVELOPE

Paul C. Wanzer, Tarrytown, N. Y.

Original application May 10, 1935, Serial No. 20,713. Divided and this application February 1, 1936, Serial No. 61,884

5 Claims. (Cl. 282—12)

The invention is concerned with improvements in office business stationery. It comprises arrangements which serve to reduce materially the time required for the performance of the office work in connection with the disposition of a business item such as the preparation of the various forms, and envelopes, and the mailing and filing of the respective papers. It affords advantages not only as to convenience and time consumed in manufacture and use, but also eliminates errors in transcribing of data and association of papers such as in the incorrect addressing of envelopes and the placing of the various papers in wrong files or envelopes.

15 This application is a division of my co-pending application filed May 10, 1935, Serial No. 20,713.

An important feature of my invention to which the present application is directed resides in the continuous form of the stationery including associated envelopes, and presents advantages both as to the method of making the stationery and convenience and economy in the use thereof. With such an arrangement the whole form may be fed into a suitable office machine as a continuous strip or large sheet and the proper data be impressed on the respective forms and envelopes. This results in the emergence of a succession of complete individual units, each relating to a particular business item or transaction, and 30 each having joined therewith one or more envelopes with the desired data thereon. The respective units may then be detached and the various papers of the unit or set detached from each other and properly disposed of, as by the selective insertion of various papers in the corresponding envelope, or envelopes, and the mailing and filing of the several parts.

In one of its particularly important aspects my invention is concerned with the provision of a compound envelope and data unit comprising sections which serve the functions of transmitting business data while simultaneously forming parts of the envelope. The unit as a whole is a sealed article adapted to be mailed and may comprise 45 one or more sheets of data or letter material to be transmitted including, if desired, duplicate, or partially duplicate sheets, so that the sendee can retain a copy and return one or more of the papers in accordance with common business practice.

In accordance with the principles upon which this compound unit is based it may be manufactured as a self contained article completely sealed, if desired, for mailing but provided with data sheets and carbon material so arranged that the

unit can be inserted in a transcribing machine and the current data relating to a particular item and sendee applied in the proper spaces, both exteriorly of the envelope and on the forms within, all without actual access to the interior. Usually the unit will have superimposed on, and attached to it, successive layers of various data sheets to be retained by the sender, and the current data will be applied thereto simultaneously with the preparation of the envelope and its inner contents. After the application of the data the various sections can be readily separated and appropriately distributed.

Similarly to the methods of manufacture and utilization of other forms and applications of my invention, this compound unit may have various data sheets associated therewith externally of the unit, and the whole assembly may likewise be produced in continuous form, affording thereby additional advantages as to economy and convenience of manufacture and use.

Various other applications and forms of my invention and the advantages derived therefrom will be in part indicated in the following description and in part rendered apparent therefrom in connection with the annexed drawings.

To enable others skilled in the art so fully to apprehend the underlying features hereof that they may embody the same in the various ways contemplated by this invention, drawings depicting typical arrangements and indicating methods of manufacture and use have been annexed as a part of this disclosure and, in such drawings, like characters of reference denote corresponding parts throughout all the views, of which:

Fig. 1 shows an arrangement of business forms and carbons and envelopes all in continuous form with the units arranged end to end;

Fig. 2 is a partially fragmentary view with portions of sheets torn away or rolled to illustrate better the parts comprising a typical unit;

Fig. 3 depicts another assemblage of data sheets and envelopes, in continuous form extending in the vertical direction with the successive units joined at their top and bottom edges;

Fig. 4 is a view corresponding to Fig. 3 with the various sections folded down to show more clearly the respective layers including an envelope;

Fig. 5 is a plan view of another typical example of a continuous form of compound stationery units;

Fig. 6 is a partially expanded perspective view of one of the units of Fig. 5;

Fig. 7 is a perspective view of one of the envelopes and carbons of Fig. 6;

Fig. 8 is a cross-sectional view of a modified form of envelope;

Fig. 9 is a plan view of stationery material in continuous form having associated therewith a novel type of compound envelope and enclosed data form sheet;

Fig. 10 is an expanded view of one of the complete units of Fig. 9;

Fig. 11 is a view of one of the compound envelope units of Fig. 10 parts of the envelope being rolled over to disclose better the arrangement; and

Fig. 12 is a similar view of a modified envelope unit including an additional data sheet.

Figs. 1 and 2 illustrate one form of my business stationery in continuous form. As a primary feature it involves the association with the envelopes of one or more business forms including suitable carbons for the appropriate transfer of data onto the various forms and envelopes usually at a single operation. Each unit such as the detached set of Fig. 2 comprises a series of superimposed forms, carbons, and one or more envelopes with appropriate data relating to a certain class of business of a particular concern initially impressed on the respective sheets prior to assembly.

As shown in Fig. 2, each unit comprises a snap-out form bound together at the top edge by suitable means as by stapling shown at 20 extending through the marginal supporting strips. Such a set would usually include feather edge one-time-use carbons, one or more of which carbons may be spot carbons in accordance with the data to be transferred to the next underlying sheet. The series of business forms are shown at 21, 22, 23 and 24, with intervening carbons at 25, 26 and 27. The set includes one or more envelopes in accordance with the requirements relating to the office practice and nature of the business matter in connection with which the stationery is to be used. One such envelope is shown at 28. This particular envelope is adapted for mailing purposes. A spot carbon 29 serves to transfer to the mailing envelope the name and address of the person—Richard Roe—in connection with whom the transaction is conducted. Other data typed in the spaces 30 will be selectively transferred to the various forms and envelopes, in accordance with the disposition of the carbon material.

The typed current matter may be applied either while the stationery matter is in attached continuous form, or as detached individual units, in accordance with the class of business machines employed by the user, and the nature of the business involved. In either case after the desired data have been applied each unit comprises a complete assemblage of all the necessary papers, records, and corresponding envelopes relating to a particular business item. The file envelopes and mailing or transfer envelopes relating to each business item with the desired data applied, are each positively attached to the particular item to which they relate.

Each unit or set may then be taken and the sections of each individual unit separated so far as is desired, and appropriately associated and distributed. Provision is made for rendering the sections of a given set readily separable from each other, and this may be accomplished through the application of appropriate perforations. For example, each of the business forms 21 to 24 may be provided with perforations along the lines 32 and the envelope 28 shown along the line 33 of

its upper sheet and the line 34 of its lower sheet. By simultaneously grasping the upper and lower edges all carbons and waste edges may be removed simultaneously. Such of the various papers as are to be inserted in the envelopes are so disposed of. With the envelopes associated with the papers, as described, all opportunities for the many errors which frequently arise, and in some instances are so serious, where the envelopes are typed and made out as a separate operation, are eliminated. The present invention assures that the envelopes must correspond in data with the form sheets, and that the respective forms will be inserted in the proper envelopes.

The arrangement presents advantages as to the manner of manufacture as well as in its use. In addition to the several data and carbon sheets the envelopes are made in continuous form by superimposing suitable sheets of material and folding over or securing the sheets together at appropriate points. In the particular form shown the front and back panels of the envelope 28 are formed by folding over a single sheet along a central line which then becomes the bottom edge and applying adhesive at suitable intervals to secure the layers together along strips corresponding to the ends of the respective envelopes. The perforations 35 may divide this strip of adhesive so that upon separation of the units a portion of the adhesive remains on the end edges of each of the respective adjoining envelopes and the corresponding end edges of the respective envelopes are sealed. A sealed end of this character is shown at 36 in Fig. 2. Where the top and bottom panels of the envelopes are formed from independent sheets as shown in Fig. 2 then the bottom edge will be sealed by a strip of adhesive 36a.

The invention may assume other forms such as that shown in Figs. 3 and 4. The continuous form of combined business data sheets and envelopes is there shown as extending successively in a single strip in a vertical direction in the plane of the drawings. Two complete units are shown with divisions along the lines 31. It comprises a plurality of business form or data sheets 38, 39 and 40 and an envelope 41 with intervening carbons 42, 43 and 44. The sheets of the respective materials are attached along the left edge by suitable means such as by cementing. No data are shown in Fig. 4 on the various sheets other than the top one but it will be understood that various suitable spaces and data will be provided initially, prior to assembling of the respective layers, and that further current data will be simultaneously impressed on the respective sheets and envelopes of each unit as used.

The single envelope per unit in this case is an open end type of envelope with a gummed loose flap 45. In Fig. 4 the extreme top edges of the two envelope sheets are shown slightly separated to indicate more clearly that there are two sheets, but with an envelope having an open end at the right as depicted, the upper as well as the lower and left edges will normally be sealed together. These gummed strips are indicated by the space lying outside the dotted lines 46 of Fig. 3. The envelope material extends to the right a small distance beyond the other sheets as shown at 47. This is for convenience in the insertion of individual papers in the envelopes and sealing thereof. The same result may be obtained, that is the inside length of the envelopes may be made greater than the data 75

sheets by suitable off-set perforations adjacent the left marginal supporting edge of the continuous strip. Perforations for the top layer of material are shown on the line 48.

5 A still further adaptation of my invention is illustrated in Figs. 5, 6 and 7 in which Fig. 5 shows a continuous form extending by successive compound units in vertical direction. The data sheets may be of the continuous fan-fold type, or 10 a series of single strips, or both, secured together at the left edge. As depicted in the expanded unit of Fig. 6 the data sheets comprise a fan-fold 49 connected together at alternate edges but adapted to be readily separated along these 15 edges after the unit has had the desired data applied. Continuous or repeat carbons can be employed and readily inserted between the appropriate folds in this type of construction, a fragmentary portion of a carbon extending between 20 the top and the second layer being shown at 50.

The complete strip includes envelopes of any desired number and with appropriate shape and data initially applied thereto. Two such envelopes are indicated in Fig. 6 at 51 and 52 respectively. Envelope 52 may be a plain open top type, for example, and adapted for filing purpose. Envelope 51 may be as shown in Fig. 7 with the lower and the left and right edges cemented as shown by dash lines at 53. The lower 30 panel may have its upper section 54 thereof readily detachable as by perforations or scoring along a line coinciding with the scoring 55 of the top layer. With the portion torn off at the perforations, the flap part 54a of the top sheet can 35 be folded over backward for sealing the envelope on the gummed surface 56. Such an envelope would be appropriate for mailing. A spot carbon 57 enables the name and address of the sendee to be impressed in the space blocked out at 58 which corresponds with the typing space 59 of the 40 top layer of stationery material. The left binding edge may be made freely separable from each unit by perforations extending through the envelope material along the lines 60, and through 45 the fan-fold form along the line 61.

The respective units, as in previous cases, may be separated by cutting along the lines 62; or may be made freely separable by the provision of scoring or perforations as shown.

50 Fig. 6 illustrates a typical detached unit. The construction and arrangement enable a series of these to be made in continuous strip form as has been illustrated and described in connection with Fig. 5, but instead of feeding a strip thereof into a machine, the individual blank units may be detached and used independently as occasion arises. Each unit as detached is complete and requires no additional folding or arranging.

55 In certain cases it may be desirable to provide envelopes of somewhat larger capacity, particularly for filing purposes. A cross section of a modified form of envelope of this nature is shown in Fig. 8 comprising a bellows type envelope with the sides expanded as here shown. This type can be conveniently made in a continuous strip of a single sheet for example. In the cross section of Fig. 8 the material is continuous from the left edge extending along the upper side, through the normally flatly folded bellows 65, the lower 60 side, and the bellows 65¹ at the left. The final edge is cemented to the upper side at 66. This envelope could be used conveniently for example with the arrangement of Figs. 3 to 6. Perforations are provided at 67 to enable the envelope 65 to be readily detached from the left binding edge

simultaneously with the other sections of a unit.

In general the shape, and method of closure, of the envelopes will depend upon the purposes for which intended, including varied forms of flaps and with the edges closed or open, and where intended to be closed, may be so adapted through the use of such well known devices and means as gummed portions, string fasteners, and metal clasps.

5 A mailing unit and arrangement of business forms affording exceptional advantages of convenience and efficiency of handling business matter is illustrated in Figs. 9 to 12 inclusive. Fig. 9 shows the arrangement as a single strip form comprising a succession of units extending vertically in the drawings. One of the units is shown expanded in Fig. 10, and includes as many exterior office forms as desired, two such being shown at 68 and 69 respectively. The particularly important feature, which I will now describe in some detail, is the mailing unit 70. This is shown generally in the rear of Fig. 10, and more fully in Fig. 11, or in the further form of mailing unit of Fig. 12. Referring to Fig. 11 the more simple arrangement there shown includes 20 a front and a back section of an envelope indicated at 71 and 72 respectively. The interior of the envelope has suitably disposed transfer material, for the transfer of current data to the inner face of the rear section, here shown as spot 25 carbons 73 and 74. Each section will have applied thereto prior to assembly, suitable permanent data, with blank spaces for the application of current data. For a large class of business correspondence, the envelope unit can be manufactured and come to the user as an entirely sealed article. A convenient means of manufacture is to cement the two sections together 30 completely around the outer edge as indicated by the border 75. In Fig. 11 two corners of the 35 upper sheet of the unit are shown rolled over, but this is merely for the purpose of better illustrating the arrangement.

A complete understanding of the principles of the arrangement and its purposes and advantages can be more readily obtained from a description of the stationery material and operations in a typical example such as in the case of a public utility required to send out enormous 45 numbers of statements of charges. The stationery may be manufactured in continuous form as in Fig. 9; or as individual units corresponding to Fig. 10. Similarly the current data may be applied either while in strip form, or as individual units, dependent upon the nature of the 50 business and type of machines employed. The desired data will be applied to the top sheet and simultaneously transferred to underlying sheets in accordance with the disposition of carbons or transfer media. Fig. 10 shows an intervening 55 carbon 77 designed to transfer all of the data to the second office sheet 69, which may be a duplicate of top sheet 68. A part carbon 78, however, serves to transfer only the name and address of the sendee to the front face of the envelope unit 70. These data will of course appear in the space 79 of each sheet including both sheets of the mailing unit 70. The spot carbon 74 serves to transfer these data to the second sheet thereof. The date, amount of the 60 charges, meter number, and folio number will be transferred to the inner face of the bottom envelope sheet 72 through the medium of the 65 spot carbon 73.

70 After all the data have been applied, the sev- 75

eral sections of a unit are detached from the left binding edge. For this purpose there will have been provided perforations 80 extending through all of the sheets including the envelope unit and excepting the carbon sheets. The left marginal supporting edges will have been secured together originally, as by stitching 81 for example.

The completely sealed envelope unit 70 is now ready for mailing. When received the addressee tears off the edges at the perforations 82, and he has at hand the bottom sheet 72 thereof with the complete correspondence or information. In the correspondence unit shown this envelope sheet 72 is substantially a duplicate of the top sheet 68 retained by the sender.

The relatively simple business stationery unit and operation just described may be varied greatly as to details of arrangement and type of the forms, and may include, for example, filing envelopes and other matter specifically disclosed in connection with other figures. The mailing unit likewise may assume other forms, one such modified form appearing in Fig. 12. In this case the unit includes three sheets all secured together originally at the outer border similarly to Fig. 11. The lower sheet 84, and the topmost sheet 85, comprise the outer sheets of the envelope proper enclosing an intermediate sheet 86. In the specific illustration the under faces of sheets 85 and 86 have carbon spots similarly applied; and the upper faces of sheets 84 and 86 will be similar as to the data appearing thereon. Utilizing this form, therefore, the sendee has two copies 84 and 86 after opening the letter, one of which he can retain, and the other return to the sender.

It will be apparent that the principles disclosed can be utilized to advantage in connection with many classes of business, and that the manner of disposing and arranging the data within the interior of the mailing unit can be varied to suit aptly a great many uses. Signatures can be so transferred, and concealed orders signed for example.

It will be understood that throughout the description and drawings thereof the several illustrated forms are selected as being typical of the applications of the various principles of my invention; and that the terminology employed is merely for the purpose of description. By the term paper or stationery material I mean to include the various forms of material adapted and variously employed for stationery purposes such as cloth, fibre and any of the various transparent or translucent forms of sheet material of cellulose derivative.

It is intended that the foregoing description in connection with the illustrative drawings will so fully reveal the g'st of this invention that others can, by applying current knowledge, readily adapt it for various utilizations by retaining one or more of the features that, from the standpoint of the prior art, fairly constitute essential characteristics of either the generic or specific aspects of this invention and, therefore, such adaptations should be, and are intended to be, comprehended within the meaning and range of equivalency of the appended claims.

Accordingly, I claim as new and desire to

secure the following by Letters Patent of the United States:

1. Business stationery in continuous form comprising sheets of business forms, having similar forms arranged successively and connected at their adjacent edges and a sheet of envelopes with the envelopes likewise arranged successively and connected at their adjacent edges, said sheets being superimposed and having respectively marginal strips with said strips connected together and the material being arranged in suitable relation and order to provide successive edgewise connected units, each unit comprising business forms and an envelope arranged for the simultaneous impression of data thereon while in assembled form.

2. Business stationery in continuous form comprising sheets of business forms and a sheet of envelopes, the business forms and the envelopes being arranged in successive edgewise fashion respectively, and said sheets being superimposed in layers and attached together by marginal strips; and carbons appropriately inserted between said sheets, said sheets being arranged to provide successive units of superimposed forms, carbons and an envelope and adapted for the simultaneous impression of data thereon, and each sheet being perforated at suitable points for the ready detachment of a unit.

3. Business stationery in continuous form combining layers of business forms, carbon paper and continuous envelopes respectively, superimposed one on the other and attached together by marginal strips, each layer comprising a continuous succession of the respective elements connected at their adjacent edges, and said layers being arranged in suitable order and relation to provide successive units, each unit comprising a business form, carbon and envelope and adapted for simultaneous impression of the desired data, and each layer being made readily separable at suitable points for the ready detachment of the corresponding form and envelope of a unit as a complete set.

4. Business stationery comprising superimposed sheets of business forms, transfer paper and envelopes in continuous form with the business forms arranged successively and detachably connected at their adjacent edges, and the envelopes similarly arranged and connected respectively to provide in the superimposed relation successive edgewise connected units each comprising a form and an envelope, said sheets being joined together by a supporting strip along a corresponding side edge, and each having weakened lines adjacent said strip and between successive units to enable ready detachment of individual units.

5. Business stationery comprising a plurality of superimposed sheets of stationery paper, one of said sheets comprising successive business forms, a second sheet comprising successive front panels of envelopes and a third sheet comprising successive rear panels of envelopes, the respective elements of a sheet being detachably connected together at adjacent edges, and the elements being arranged one above the other in units comprising a business form and an envelope.
